UNITED STATES PATENT OFFICE.

JOSEPH D. OPPENHEIMER, OF PHILADELPHIA, PENNSYLVANIA.

DESIGN FOR A HAIR-PIN.

SPECIFICATION forming part of Design No. 15,475, dated October 21, 1884.

Application filed July 21, 1884. Term of patent 7 years.

To all whom it may concern:

Be it known that I, JOSEPH D. OPPENHEIMER, a citizen of the United States, residing in Philadelphia, Pennsylvania, have invented or produced a new and original Design for a Hair-Pin, of which the following is a specification.

My design is fully shown in the accompanying drawings, in which Figure 1 is a face view, and Fig. 2 a side view, of my hair-pin.

The front and back of the pin are flat, and the prongs are slightly curved, as shown in Fig. 2, and each prong has an upper and lower laterally-waved portion, *a*, and an intervening straight portion, *b*.

I claim—

The design for a hair-pin, said design consisting of the prongs flat on front and back, but having upper and lower laterally-waved portions, *a* *a*, and intervening straight portion, *b*, as shown and described.

In testimony whereof I have signed my name to this specification in the presence of two subscribing witnesses.

JOSEPH D. OPPENHEIMER.
